George Wright ATTORNEY.

UNITED STATES PATENT OFFICE.

LEONARD PADEN, OF COLUMBUS, OHIO.

MATCH-BOX HOLDER.

No. 921,445.

Specification of Letters Patent.

Patented May 11, 1909.

Application filed May 2, 1908. Serial No. 430,616.

To all whom it may concern:

Be it known that I, LEONARD PADEN, a citizen of the United States, residing at Columbus, in the county of Franklin and State 5 of Ohio, have invented certain new and useful Improvements in Match-Box Holders, of which the following is a specification.

My invention relates to improvements in a match box holder arranged to feed the 10 matches into an auxiliary chamber or tray having ready access thereto, and a provision for storing the burned matches in the same chamber or receptacle from which the fresh matches are delivered; the delivery of the 15 matches and the provision of a space for the reception of the burned matches takes place through gravity. The box or receptacle is made so as to be readily taken apart for the insertion of the usual pasteboard match box, 20 whereupon it may readily be secured together for use.

In the drawings which are hereto attached and hereby made a part of this specification, Figure 1 is a perspective of my improved 25 match box holder with a part broken away; Fig. 2 is a vertical transverse section through the same; Fig. 3 is a view of the tray member separating the burned and fresh matches, detached, showing the guiding means therefor 30 in its travel downwardly as the fresh matches are extracted from the box; Fig. 4 is a view of the box holding chamber; Fig. 5 is a view of the detachable member forming the top and front.

35 Referring to the drawings in which the same numeral indicates the same part throughout, 1 is the box holding member having the extension 2 thereon at the front side thereof, forming an auxiliary chamber 40 into which the matches are delivered through gravity and from which the matches may be readily picked up for use; 3 is the detachable member so constructed as to form the top 4 and the front 5 in one piece, and having the 45 slot 6 formed therein whereby access is provided from the outside to the interior of the receptacle or box holding chamber 1; this slot is clearly shown in Figs. 1 and 2. Preferably struck up from the back side of the 50 box member 1 is the lug or hook 7 adapted to protrude through the opening 8 formed in the top 4, whereby the detachable member 3 is secured to the principal box member 1 at the back side of the top 4 thereof; the detachable member 3, on its front side 5 is cut to 55 form the tongues 9 and 10, which tongues are

adapted to be inserted through the openings shown at 11 and 12 formed in the sides of the auxiliary chamber 2. In this manner the member 3 is securely fastened to the front 60 side of the box holding chamber 1; the tongues 9, 10, may be let into the openings 11, 12, as to permit the member 3 to be rotated outwardly to open the box and inwardly to close the same for operation. 65

The member 3 having been removed, a match box such as is usually found on the market, having the cover removed therefrom, is inserted into the box holding chamber 1, to occupy the position shown in Figs. 1 70 and 2 and 4 at 13; this being full of matches, the box holding member 1 may be held with the back 14 thereof in a horizontal plane while the remaining members are being secured in place. The tray member 15 is then 75 positioned by sliding the same into the upper end of the pasteboard box 13, the guide lugs 16 being inserted between the side walls of the member 1 and the sides of the pasteboard box 13, whereby the tray member 15 is kept 80 in alinement as it descends; the lugs 17 are adapted to be positioned upon the outer edges of the pasteboard box 13 and the box holding member 1, as appears in Fig. 1. When thus positioned the tray member 15 85 rests upon the matches in the pasteboard box 13, and has the guide lugs 16 and 17 rather loosely positioned between the parts mentioned, the tray member 15 is free to move downwardly upon the top surface of the receding matches. When the pasteboard box 13 has been thus positioned and the tray 15 90 has been thus placed in position, the detachable member 3 is applied with the top member 4 engaged by the tongue 7, and the tongues 9 and 10 entering the openings 11 and 12 provided therefor; thus the member 3 is securely positioned upon the box holding member 1, the guide lugs 17 lying between the front portion 5 and the edges of the boxes 13 100 and 1, to slide freely upwardly and downwardly. The slot 6 in the top of the member 3 is directly above the tray member 15, as seen. A slit or opening 18 is provided at the top side of the back 14 for hanging my improved match box on a nail or pin at any desired point. 105

The pasteboard match box 13 being opened along its entire top, which becomes its front side as it is positioned in the box holding member 1, as shown in Figs. 1 and 2, the matches 19 are free to roll outwardly into

the receptacle or auxiliary chamber 2, an opening 20 being left between the front portion 5 of the detachable member 3, and the bottom 21 of the box holding member 1; the 5 matches will move outwardly and fill the auxiliary chamber 2 entirely through gravity, and as they are lowered in the box 13, the tray member 15 will move downwardly through gravity, guided by the lugs 16 and 10 17 mentioned above. When a match has been used, the burned end may be inserted through the slot 6 and thereby dropped upon the tray 15, upon which the burned ends will gradually accumulate, and as the box is 15 emptied of fresh matches, the burned matches will occupy their places, moving gradually downward upon the tray or partition member 15. It is seen that the burned matches and the fresh matches are kept entirely separated 20 from each other, and I therefore not only provide a convenient receptacle for the burned matches where they are entirely out of sight, but also prevent them from mingling again with the fresh matches. When all of 25 the matches have been used, the detachable member 3 may be removed by withdrawing the tongues 9 and 10 from the openings 11 and 12, and then lifting the member 3 upwardly to disengage it from the tongue 7; the 30 tray member 15 may then be lifted out of the box 13, which latter may then be removed and a fresh box inserted in its place, whereupon the tray member 15 may be replaced and the adjustable member 3 attached again 35 and the new matches will be ready for use.

Some variations in the construction, to accomplish the same results as herein set forth, may be made, and I do not confine myself to the specific construction herein 40 shown, but desire to include in the appended claims any construction which properly falls within the scope of my invention.

It is seen that my invention comprises a match box holder comprising preferably 45 only three pieces or members, which are readily connected and disassociated, and which provides in the one receptacle a place for the burned match ends, as well as for the fresh matches, the burned matches taking 50 the place of the removal of the fresh matches as they are used, the feeding of the matches

and the providing of the space for the burned matches being accomplished by gravity.

What I claim is:

1. A match box holder having a match holding chamber and an auxiliary chamber, a match box in said holding chamber, a sliding tray positioned therein, a member adapted to be applied to said holder to form the top and front sides thereof to inclose said box and tray, and means of access through such member to said tray.

2. A match box holder comprising a box holding chamber, a delivery chamber, a detachable member forming the top and front 65 for said box holding member and leaving communication between said chambers, a tray member positioned transversely in said box holding chamber and free to slide therein, said detachable member being slotted to 70 provide access to said tray member.

3. A match box holder comprising a box holding chamber, an auxiliary chamber into which the matches pass by gravity, a tray member positioned within said box upon the 75 matches therein and being free to move downwardly as the matches recede, a detachable member secured upon said box holding member and being slotted to provide access to said tray member, and guide members for said tray member arranged slidably between said box and said detachable member.

4. A match box holder comprising a box holding chamber, a delivery chamber, said 85 box holding chamber being adapted to receive a supply of matches to be fed into said delivery chamber through gravity, a tray member adapted to be positioned upon said matches to move downwardly thereon as 90 said matches recede, a member adapted to be applied to said box holding portion to form the top and front sides thereof to inclose said matches and tray and being slotted to permit the insertion of burned matches 95 on to said tray.

In testimony whereof I affix my signature in the presence of two witnesses.

LEONARD PADEN.
